RUDOLPH BECKER, OF ROSELLE PARK, NEW JERSEY, ASSIGNOR TO THE SINGER MANUFACTURING COMPANY, A CORPORATION OF NEW JERSEY.

THREAD CUTTER.

1,422,407.

Specification of Letters Patent. Patented July 11, 1922.

Application filed September 6, 1918. Serial No. 252,938.

To all whom it may concern:

Be it known that I, RUDOLPH BECKER, a citizen of the United States, residing at Roselle Park, in the county of Union and State of New Jersey, have invented certain new and useful Improvements in Thread Cutters, of which the following is a specification, reference being had therein to the accompanying drawings.

This invention relates to an improvement in thread-cutting means for sewing machines.

The objects of the invention are to provide a simple and efficient thread-cutter operating with a shearing action, and to provide means thereon for guiding one limb of a thread-loop within the jaws of the shears.

The thread-cutter in the embodiment shown is located in the work-arm of the machine and comprises a shear blade pivotally connected to the work-arm, a second shear blade having a floating pivot, a pivotal connection between the blades, means carried by one of the blades for seizing the needle-loop and deflecting one limb thereof into the space between the blades, and means for actuating the blades.

Referring to the accompanying drawings, Fig. 1 is a side elevation of a sewing machine having my thread-cutter attached thereto. Fig. 2 is a longitudinal section through the machine below the upper wall of the work-arm, and showing the thread-cutter; Fig. 3 is a view of the right-hand side of Fig. 2, showing the thread-cutter on an enlarged scale, and Fig. 4 is a section of the work-arm on substantially the line 4—4 of Fig. 3, the blade 8 being shown in elevation.

In the drawings 1 is the machine base having a forwardly projecting work-arm 2 and overhanging arm 3, the latter carrying the usual needle-bar having a needle 4. Pivotally mounted at 5 in the work-arm 2 adjacent the looper 4' is a member in the form of a bellcrank-lever, one arm 6 of which forms one of the shear blades of the cutter, the other arm 6' being connected to an operating link 7. A second shear blade 8 has a pivotal connection at a point 8' intermediate its ends with a spring wire or other link 9, the latter being bent downwardly and secured to the side-wall of the work-arm by a screw or other means 9' as shown in Fig. 4. The blade 8 also has a pivotal connection at 10 with blade 6. The back edge of blade 8, or the edge opposed to its cutting edge, has a cam surface at 8² adapted to engage with a straight portion or abutment 8³ on the inner wall of the work-arm as the blade moves on its pivot 10. The spring wire link 9, in addition to serving as a floating fulcrum for the blade 8, forms a yielding means for holding the cam-surface 8² against the surface 8³, thus opening the blades when blade 6 is retracted, and bears downwardly against the blade 8 to thereby maintain the cutting edges of the blades always in contact. It will be noticed that the blade 6 has a fixed pivot, while the blade 8 has a floating one, and a toggle is formed between the pivot point 5 of blade 6, the bearing point of cam 8² on surface 8³ and the point of connection of the blades at 10. Extending laterally from the end of blade 6 is a projection or nose 11, which acts to enter a thread-loop held by the looper and to deflect and detain one limb thereof for severance by the blades. The operating link 7 may be actuated in any desired manner, and in the embodiment shown is connected to a stop-motion mechanism substantially the same as that shown in the patent to C. M. Horton, No. 1,051,998, dated February 4, 1913. It is obvious, however, that the actuating means for closing the blades 35 may be applied in many ways and to either blade.

At predetermined periods in the operation of the machine a bellcrank-lever 12 (Fig. 2) at the lower end of the stop-motion mechanism is moved to actuate link 7 against the tension of a spring 13. This causes the bellcrank-lever 6, 6' to move on its pivot 5 and through the pivotal connection 10 and the bearing of the cam 8² on surface 8³, blade 8 is oscillated about said pivot 10. This causes a relative closing movement of the two shear-blades and as the thread is caught between them it is severed. It will be noticed that as blade 6 moves toward the surface 8³ the bearing point of the curved surface of the cam 8² on this surface 8³ moves nearer the pivot 10 thus shortening its leverage and accelerating the relative movements of the two blades. This gives a comparatively slow 105 relative movement of the two blades as the thread is being caught by the projection 11 but as the cutting edges come together after the thread is caught the actual cutting is accomplished by a rapid relative movement 110

of the cutting edges similar to a chopping movement thus giving a more reliable operation. Because of this movement of the blade 8 given by the cam, the cutting edge is moved 5 away from the surface 8² sufficiently to cut the thread when it is substantially in line with the needle opening, but when the blades are opened the cutting edge of blade 8 is retracted out of the line of the needle opening 10 and so will not interfere with the thread or needle, as clearly shown in Fig. 3. The cam surface 8² and the abutment 8³ may be dispensed with if desired in which event the spring 9 would form a yielding means for 15 closing the shear-blades to cut the thread upon operation of the blade 6 instead of the positive means obtained with the use of cam 8² and abutment surface 8³. In the movement of blade 6 the projection 11 has previously entered the thread-loop leading as 20 usual from the looper and deflected and detained one limb of the same, which limb is severed by the closing of blades 6 and 8.

Having thus set forth the nature of the 25 invention, what I claim herein is:

1. In a sewing machine, a thread-cutter comprising a cutting blade having a fixed fulcrum, a second cutting blade having a floating fulcrum and a cam-surface, a pivotal 30 connection between said blades separate from the floating fulcrum, means for actuating one of said blades, and means coacting with the cam-surface for swinging the other blade about the pivotal connection between the 35 blades.

2. In a sewing machine, a thread-cutter comprising a cutting blade having a fixed fulcrum, a second cutting blade coacting therewith having a floating fulcrum and a 40 cam-surface, a pivotal connection between said blades intermediate their fulcrums, means for moving said first blade on its fulcrum, and means coacting with the cam-surface to move the second blade about the 45 pivotal connection between the blades.

3. In a sewing machine, a work-support, stitch-forming mechanism including a reciprocating needle and a complemental loop-taker, a fulcrumed cutting blade, a second 50 fulcrumed cutting blade coacting with said first mentioned blade and having a link connection with the machine, one of said blades having a portion so formed and positioned as to enter between the limbs of a needle-loop below the work-support, a pivotal connection between said blades intermediate their fulcras, and means for actuating said blades.

4. In a sewing machine having stitch-forming mechanism and a stop-motion mechanism therefor, a cutting blade pivotally mounted on the machine, a second cut-

ting blade having a link connection with the machine and a pivotal connection with said first blade, and means operated by the stop-motion mechanism for actuating said blades. 65

5. In a sewing machine, a thread-cutter comprising a pair of pivotally connected shear blades, yielding means for maintaining the cutting edges of said blades in contact, 70 said means forming a fulcrum for one of said blades separate from the pivoted connection between the blades, and means for actuating said blades.

6. In a thread-cutter, a pivotally mounted 75 shear-blade, means for moving it about its pivot, a second shear-blade pivoted to the first mentioned shear-blade at a point spaced from the first mentioned pivot, a cam on said second shear-blade, and a fixed abutment 30 against which said cam reacts as a fulcrum during the movement of the first mentioned blade.

7. In a sewing machine, a thread-cutter comprising a blade having a fixed fulcrum, 35 a second blade pivoted to the first blade intermediate its cutting edge and its fulcrum, the second blade being provided with a cam, means on the machine cooperating with the cam, yielding means providing a floating 90 fulcrum for the second blade and acting to retain the cam against its cooperating means, and means for operating one of the blades.

8. In a sewing machine, a thread-cutter comprising a pair of pivotally connected shear-blades, one blade being pivoted to the machine and the second blade having pivotal connection with the first blade, a resilient link secured to the machine and having pivotal connection with the second 100 blade, and means for operating one of said blades.

9. In a sewing machine, a thread-cutter comprising a pair of pivotally connected shear-blades, a cam on one of said blades, 105 means on the machine cooperating with said cam, a yielding element for maintaining said means and cam in cooperation and the cutting edges of the blades in contact, and means for actuating one of said blades. 110

10. In a sewing machine, a work-support, stitch-forming mechanism including a reciprocating needle and a complemental loop-taker, and cooperating shear-blades mounted on the same side of the work as the loop-taker, one of said blades being formed with a loop-dividing point which is so positioned as to be projected during the closing movement of said blades into the last needle-loop while held spread by the loop-taker. 115 120

In testimony whereof, I have signed my name to this specification.

RUDOLPH BECKER.
